APPARATUS FOR DISPERSING LIQUID

Francis Stephen Pilkington, Hull, England, assignor to Charles D. Holmes and Company Limited, Hull, England

Application May 5, 1943, Serial No. 485,776
In Great Britain December 15, 1942

13 Claims. (Cl. 266—38)

This invention relates to devices for feeding heavy liquids and for pumping such liquids from one point to another.

The term "heavy liquid" used above and throughout this specification is intended to mean a substance of high specific gravity in a state of fluidity, and in particular low melting point metal alloys in a heated molten state.

Low melting point metal alloys are extensively used for filling pipes and tubes prior to their being bent either by hand or by machine methods but in spite of this large use of these alloys, no apparatus at present exists for transferring the molten metal from a reservoir or receptacle in which they are melted to the pipes to be filled. It has certainly been proposed to feed the metal by gravity through a tap but this can only be accomplished with difficulty on account of sludging at the tap due to cooling of the molten metal.

The low melting point metal alloys used for filling pipes are liable to oxidation and to avoid this disadvantage are usually submerged in water which is kept hot for the purpose of melting the alloy and maintaining it in a molten state. To accomplish the filling of pipes, it has been necessary to ladle the molten metal with the result that water and metal are poured into the pipes so causing the protective film of oil customarily provided when manipulating copper and similar pipes to be washed out.

A principal object of the present invention is to provide a device for feeding or transferring molten low melting alloys from a reservoir or other receptacle to another point which is intended to eliminate any possible disadvantage due to unintentional cooling of the metal alloy and at the same time secure efficient operation with safety with avoidance of the possibility of oxidation so that the molten metal may be taken from the reservoir to a point convenient for filling pipes or other purposes free or substantially free from the water in which it is submerged.

To this end, according to the present invention, the device comprises a chamber capable of containing a column of water which has a port at its lower end for the admission of heavy liquid, a port at its upper end opening to atmosphere and means for feeding fluid under pressure to the upper end of the chamber such that after closing the ports heavy liquid in the bottom of the chamber will be expelled from the chamber through an outlet provided for that purpose by the fluid pressure created in the chamber acting through the column of water.

When the ports are again opened the fluid pres-

sure is released and any heavy liquid in the delivery will return to the chamber so preventing possible trouble due to the heavy liquid remaining in the delivery.

5 According to a further feature of the invention, the ports are connected together for simultaneous movement and are urged both in opening and closing direction by fluid pressure.

According to a still further feature of the invention, a non-return valve is provided for permitting water, for example the water covering a low melting point alloy, to enter the chamber to maintain the column of water therein.

According to yet another feature of the invention a baffle is provided within the chamber adjacent to the delivery outlet and so arranged as to reduce any tendency for the water or air to be forced through the heavy liquid.

According to yet a still further feature of the invention, the upper valve seats on a resiliently mounted member in order to ensure closing of the lower port.

The feeding device is particularly intended to be placed in the tank containing the molten low melting point alloy and hot water and is partially submerged therein so that only the upper end with the top port and the end of the delivery is above water. The device is preferably made fast to the tank and the line leading the fluid under pressure, for example compressed air, to the device is preferably out of the water in order to avoid appreciable heating up of the air.

In order that the invention may be clearly understood and readily carried into effect a preferred embodiment is hereinafter more fully described with reference to the accompanying drawings which are given for purposes of illustration only and not of limitation.

40 In these drawings—

Figure 1 is a side elevation of the device shown mounted in a receptacle seen in section which forms the inner compartment of a double-walled tank,

45 Figure 2 is a plan view of the device shown in Figure 1.

Figure 3 is a sectional elevation taken on the line III—III on Figure 2.

Figure 4 is a transverse section taken on the line IV—IV of Figure 3.

Figure 5 is a detail sectional view showing a baffle over the delivery outlet,

Figure 6 is a detail sectional view taken at right angles to Figure 5 showing the baffle in section,

Figure 7 is a section through the controlling valve taken on the line VII—VII of Figure 2,

Figure 8 is a front view of the ported valve chest, and

Figure 9 is a front view of the valve member.

Referring now to the said drawings and in particular to Figures 1 to 4, the device comprises a tubular chamber 1 which is closed off at its lower end by a transverse partition 2 in which is provided a non-return valve 3 of poppet type having extension guides. The upper end of the chamber 1 is closed off by an end plate 4 in which is provided a non-return valve 5 also of poppet type which seats on a member 6 having a flange 7 between which and the end plate 4 is a resilient packing. A valve rod 8, which may be adjustable as to length, connects the valves 3 and 5 for simultaneous movement.

The valves 3 and 5 are so related, or the length of the rod 8 is adjusted, that both these valves close together. Due however to the resilient mounting of the seat member 6, the valve 5 may continue to move until the valve 3 has been seated. In this way there is automatic compensation for expansion due to temperature changes since of course the initial setting of the valves will normally be done cold and clearance must be left for expansion of the rod 8.

The upper end of the valve rod 8 beyond the valve 5 is connected to the piston rod 9 of a double acting piston 10 within the cylinder 11 which is supported above the end plate 4 by brackets 12.

The lower end 13 of the chamber 1 may be of larger diameter as shown since the larger the diameter of that portion of the device the greater will be its capacity to receive heavy liquid and the larger will be the quantity delivered at each operation as will be appreciated from the explanation of the operation given hereafter. The lower end of the chamber extends beyond the transverse partition 2 and the end thereof is intended to rest on the bottom of the tank or other receptacle in which the device is used. This extension portion is provided with a number of apertures 14 for the passage of the heavy liquid and for filtering off solid bodies although this danger is small in the case of low melting point alloys since iron will float on the molten low melting point alloys available on the market.

Near the upper end of the chamber there is provided an inlet 15 for fluid under pressure and an inlet 16 associated with a non-return valve 17 for permitting water to enter the chamber whilst preventing escape of fluid therefrom. At the bottom of the chamber is an outlet aperture 18 leading to a delivery pipe 19 which terminates in a nozzle 20.

The nozzle 20 is interchangeable with nozzles of different aperture and the delivery pipe is preferably pivotable about a vertical axis and in the embodiment shown swivels in a coupling 21 on an outlet pipe 22 leading from the aperture 18 at the bottom of the chamber. A handle 23 is provided at the uppermost point of the delivery pipe 19 for the convenient moving of its free end and in order to prevent strain on the pipe a supporting bracket 24 is mounted on the outside of the chamber 1.

A baffle plate 25 is attached to the walls of the chamber in the region of the outlet aperture 18, the arrangement being such that a narrow space is left between the edge of the baffle and the transverse partition 2 through which the heavy fluid may be forced. The advantage of this baffle is that it prevents the water or water and air be-

ing forced through the heavy liquid and out through the aperture 18.

Near the upper end of the chamber 1 there is provided a valve 26 for controlling the admission of fluid under pressure to the cylinder 11 and chamber 1. The valve 26 is illustrated in detail in Figures 7, 8 and 9 and comprises a chamber having a rotatable spindle 44 on the end of which is an operating handle 27. Within the valve chamber the spindle 44 carries a valve member 45 seen in section in Figure 7 and having the shape shown in Figure 9.

The valve member 45 on its under-surface has a recess 46 and is arranged to slide over the ported chest 47. Air inlet port I leads into the valve chamber and a fluid pressure line connected to a convenient source of pressurised fluid such as compressed air is connected at 28 so that the compressed air will enter through the port I. A further port L communicates with a conduit 29 leading to the underside of the piston 10 in the cylinder 11. A third port U communicates through a conduit 30 with the upper side of the piston 10. A fourth port C communicates through a conduit 31 with the interior of the chamber 1 through the inlet 15. In this conduit 31 is a pressure regulating valve 32 provided with a handwheel 33 for regulating the flow of fluid pressure to the chamber 1.

A central port A is open to atmosphere.

The arrangement of this valve is such that with the valve member 45 in normal position the ports I and L are open whilst the ports U and A are in communication through the recess 46 whilst the port C is closed by the portion 45^A of the valve member 45.

On rotating the valve member 45 in anti-clockwise direction relative to Figure 8 the web of the valve member 45 closes the ports L and U and thereafter places the ports I and U in communication and the ports L and A in communication.

During this time the portion 45^A still blocks the port C. On the valve member 45 reaching its limit position the portion 45^A passes beyond the port C to place it in communication with the port I whilst the ports I and U are still in communication as are also the ports L and A.

In order to apply the air pressure to the chamber progressively the leading edge C¹ of the port C tapers and as the edge of the portion 45^A moves around a gradually increased area of the port C is exposed.

On reverse movement of the handle 27 and valve member 45 a reverse sequence of operations takes place when the portion C¹ of the port C avoids any disadvantages due to too rapid shut off of that port.

It is also to be noted that the pressure of the fluid in the chamber will tend to press the valve member 45 onto the face of the ported chest 47 and that in the operation of the valve when the one side of the piston 10 is applied with fluid under pressure the other side of the piston is placed in communication with the atmosphere. Thus to close the valves 3 and 5 the handle 27 is rotated to place the ports I and U in communication and the ports L and A in communication. The fluid pressure through the conduit 30 causes the piston to move downwardly in its cylinder 11 until the valves 3 and 5 are closed. The operating handle 27 is reversed to bring about opening of the valves 3 and 5 when the ports I and L again communicate as well as the ports U and A. The fluid pressure under the piston 10 lifts it and during this movement the pressure of the fluid in

the chamber by acting on the valve 5 assists in lifting it.

It will be appreciated that any other convenient construction of valve serving to regulate the fluid pressure to the cylinder 11 and chamber 1 in the above manner will serve equally well in place of the valve described above by way of example.

The device is used in a tank or other receptacle containing the heavy liquid and in the drawings is shown mounted in an inner tank 34, containing a molten low melting alloy and hot water and arranged within an outer tank 35. The minimum level for the molten metal is indicated by the line 36 whilst the water level is shown by the line 37. As iron will float on molten low melting point alloys the device must be secured to the tank in which it is used and this is most conveniently accomplished by attaching it to the bottom thereof. In the present instance rods 38 are welded or otherwise made fast to the bottom of the tank and these rods pass through apertured lugs 39 near the top of the chamber 1 and are there threaded to receive wing nuts or the equivalent 40 which, by bearing on the lugs 39, force the device against the bottom of the tank 34. Where the lower portion of the chamber is enlarged as at 13, tubes 42 extend through this enlarged portion for the accommodation of the rods 38.

In using the device it is mounted as described above in a tank or in the inner of a double tank wherein there is a heavy liquid, such as molten low melting point metal alloy covered with hot water which extends up near to the top of the device. The device is secured in position with the aid of the rods 38 referred to above and a fluid pressure line is connected at 28 to the valve 26. Now, with the handle 27 in its normal position the fluid pressure lifts the piston 10 and opens the valves 3 and 5. This permits the heavy liquid to enter the port enclosed by the valve 3 and rise up to a level of that liquid in the tank 34. Water may also flow in through the non-return valve 17 to the level of the water in the tanks 34 and 35. The pipe or other article to be filled is placed under the nozzle 20 or the delivery pipe is moved by means of the handle 23 to position the nozzle 20 above the pipe or article to be filled. The handle 27 is now moved so opening the conduit 29 to atmosphere and connecting the conduit 30 to fluid under pressure whereby the piston 10 is moved downwardly with consequent closing of the valves 3 and 5. The chamber in this condition is virtually sealed. On further movement of the handle 27 into its other limit position the fluid under pressure in addition to passing through the conduit 30 flows through the port C and conduit 31 through the aperture 15 into the chamber 1 above the column of water therein. The pressure of this fluid acting on the incom-60 pressible column of water forces it downwardly so that the heavy liquid at the bottom of the chamber 1 is forced between the baffle 25 and transverse partition 2 through the orifice 18 and up the delivery pipe 19 to be discharged through the nozzle 20. The heavy liquid will continue to be discharged until the chamber is substantially emptied of such liquid and if the operator continues to apply fluid pressure too long there will be a discharge of water which will warn him to reverse the valve 26. On reversing the valve 26 the conduit 30 is opened to atmosphere and the conduit 31 is closed whilst the conduit 29 is again connected to the fluid pressure causing upward movement of the piston 10 and opening of the 75

valves 3 and 5 which is assisted by the pressure within the chamber acting on the valve 5. The fluid pressure in the chamber is relieved through the valve 5 and on opening of the valve 3 further heavy liquid may enter through the port of that valve and any heavy liquid in the delivery pipe 19 will return to the chamber 1. Due to this return of the fluid in the delivery pipe 19 the possibility of cooling of the molten metal at the swan neck end of the delivery pipe is avoided. The operator may repeat the delivery operations until the pipe or other article is filled with heavy liquid. During the operation if there is any discharge of water, fresh water may enter in through the non-return valve 17 to maintain an adequate column of water. At all times there is water between the molten metal in chamber and the compressed air so that oxidation of the metal is avoided and possibility of the air expelling the metal in a dangerous manner eliminated.

In order that the column of water shall remain substantially the ruling temperature of the water in the tanks 34 and 35 in order to avoid any cooling of the molten metal in the chamber, a plurality of pipes 41 extend into the chamber through the walls thereof at two points one above the other so that the ambient water may circulate through these pipes and maintain the temperature of the water in the chamber 1.

During use of the apparatus the speed of delivery of the heavy liquid is always under the control of the operator as he may adjust the supply of fluid pressure by means of the valve 32 to obtain a constant rate of delivery or he may vary the angular setting of the handle 27 to alter the effective area of the port C for temporarily varying the rate of delivery.

Amongst the advantages of the apparatus it may be pointed out that it draws in a fresh charge of molten metal from the bottom so that only clean metal will enter the chamber since dross and impurities will float to the top.

What I claim is:

1. Apparatus for delivering heavy liquids such as molten low melting point metal alloys, comprising a hollow chamber capable of containing a column of water, a port at the lower end of said chamber for admission of the heavy liquid into said hollow chamber, a port at the upper end of said chamber opening to atmosphere, means for closing said ports, a discharge port at the lower end of said cylinder, a delivery conduit leading from said discharge port, and means, operable to admit gaseous fluid under pressure to the upper part of said chamber above the water such that with the upper and lower end ports closed the heavy liquid will be driven out of said discharge port.

2. Apparatus for delivering heavy liquids such as molten low melting point metal alloys, comprising a tubular housing intended to contain water, a valve at the lower end of said housing opened to admit the heavy liquid, means for operating said valve a valve at the upper end of said housing open to atmosphere, means for closing said valve open to atmosphere, a discharge port at the lower end of said housing, a flexible delivery conduit leading from said discharge port and means for admitting compressed fluid to the upper part of said housing such with said valves closed a fluid pressure will be built up in said housing to force the heavy liquid out through said discharge port.

3. Apparatus for delivering heavy liquids such

as molten low melting point metal alloys, comprising a hollow casing, valve means at the top and bottom of said casing, a discharge port opening into a delivery pipe, pressure responsive means for causing opening and closing of said valves, and means for admitting gaseous fluid to said pressure responsive means to close said valves and to said casing to create a fluid pressure therein which will force the heavy liquid out through said discharge port and said delivery pipe.

4. Apparatus for delivering heavy liquids such as molten low melting point metal alloys, including a hollow vessel, valve means at the top and at the bottom of said vessel, means for opening and closing said valve means together, a discharge port near the bottom of said vessel and opening into a delivery conduit, a baffle within said vessel such that liquid passing out through said outlet port must pass between the edge of said baffle and the bottom of said vessel, and means for admitting gaseous fluid under pressure into the top of said vessel to force heavy liquid contained therein out through said discharge port and said conduit.

5. Apparatus for delivering heavy liquids such as molten low melting point metal alloys, comprising a hollow tubular vessel, valve means at the bottom of said vessel for the admission of heavy liquid, valve means at the top of said vessel opening to atmosphere for relieving gaseous fluid pressure in said vessel, means connecting said valve means, means for causing opening and closing of said valve means, a discharge port near the lower end of said vessel and opening into a delivery conduit, and means for admitting gaseous fluid under pressure near the top of said vessel to force heavy liquid therein out through said discharge port and delivery conduit.

6. Apparatus for delivering heavy liquids such as molten low melting point metal alloys, comprising a hollow tubular vessel, valve means at the bottom of said vessel for the admission of heavy liquid, valve means at the top of said vessel opening to atmosphere for relieving gaseous fluid pressure in said vessel, means connecting said valve means, pressure responsive means for causing opening and closing of said valve means, a discharge port near the lower end of said vessel and opening into a delivery conduit, means for admitting gaseous fluid under pressure near the top of said vessel to force heavy liquid therein out through said discharge port and delivery conduit, and valve means for admitting the gaseous fluid to said pressure responsive means to close said valve means at the top and bottom of the vessel and then to said vessel to discharge the heavy liquid therein.

7. Apparatus for delivering heavy liquids such as molten low melting point metal alloys, including a hollow pressure resisting vessel, an aperture at the bottom of said vessel to permit flowing in of the heavy liquid, a valve member for closing said aperture, an aperture at the top of said vessel opening to atmosphere, a resilient seating around said top aperture, a valve member capable of seating on said resilient seating to close said top aperture, means for connecting said valve members for simultaneous movement, a cylinder, a piston in said cylinder connected to one of said valve members, a discharge port near the lower end of said vessel opening to a delivery pipe, means for admitting gaseous fluid under pressure near the top of said vessel, and valve means for admitting gaseous fluid under

pressure first to one side of said cylinder to move the piston to cause said valve members to close said aperture, then to said vessel to force heavy liquid therein out through said discharge port and said delivery pipe, and finally to the opposite side of said cylinder to cause opening of said valve members to relieve the fluid pressure in said vessel and allow further heavy liquid to flow.

8. Apparatus for delivering heavy liquids such as molten low melting point metal alloys, including a hollow pressure resisting vessel, an aperture at the bottom of said vessel to permit flowing in of the heavy liquid, a valve member for closing said aperture, an aperture at the top of said vessel opening to atmosphere, a resilient seating around said top aperture, a valve member capable of seating on said resilient seating to close said top aperture, means for connecting said valve members for simultaneous movement, one way acting valve means for admitting water to said vessel, a cylinder, a piston in said cylinder connected to one of said valve members, a discharge port near the lower end of said vessel opening to a delivery pipe, a baffle in said vessel adjacent said discharge port such that heavy liquid must pass between the edge of said baffle and the bottom of said vessel to reach said discharge port, means for admitting gaseous fluid under pressure near the top of said vessel to discharge the heavy liquid therein out through said discharge port and said delivery pipe and a three way valve which in one position connects one side of said cylinder to a source of fluid under pressure and the other side to atmosphere, in another position connects said source of fluid under pressure to the means for admitting it to said vessel and in its third position reverses the connections to said cylinder.

9. Apparatus for delivering heavy liquids such as molten low melting point metal alloys, including a hollow vessel, valve means for the admission of heavy liquid into said vessel, valve means opening to atmosphere for relieving gaseous fluid pressure within said vessel, means for opening and closing both of said valve means, a discharge port opening into a delivery pipe, and means for admitting gaseous fluid under pressure into said vessel to force heavy liquid contained therein out through said discharge port and said delivery pipe.

10. Apparatus for discharging molten low melting point metal alloys from a tank containing such alloys submerged in hot water, including a hollow vessel which is partly submerged and extends into the molten alloy, valve means at the lower end of said vessel openable to permit the molten alloy to flow in, valve means at the upper end of said vessel openable to atmosphere, means permitting part of the hot water to enter the vessel, a discharge port at the lower end of said vessel opening into a delivery pipe, means for opening and closing both of said valves, and means for introducing gaseous fluid under pressure into said vessel to create a fluid pressure therein which will drive the water downwardly in said vessel to force the molten alloy therein out through said discharge port and said delivery pipe.

11. Apparatus for discharging molten low melting point metal alloys from a tank containing such alloys submerged in hot water, including a hollow vessel which is partly submerged and extends into the molten alloy, valve means

at the lower end of said vessel openable to permit the molten alloy to flow in, valve means at the upper end of said vessel openable to atmosphere, means for connecting together said valve means, pressure responsive means for urging said valve means in closing and in opening direction, one way acting valve means for permitting hot water to enter said vessel, a discharge port near the lower end of said vessel opening into a delivery pipe leading to above the water level, means for introducing gaseous fluid under pressure into said vessel to drive out molten metal therein, and valve means controlling the feeding of gaseous fluid under pressure to said pressure responsive means and to said vessel.

12. Apparatus for discharging molten low melting point metal alloys from a tank containing such alloys submerged in hot water, as claimed in claim 11 including means for circulating the hot water in the tank through said vessel.

13. Apparatus for discharging molten low melt-

ing point metal alloys from a tank containing such alloys submerged in hot water, including a vertically extending hollow tubular vessel which is partly submerged and extends into the molten alloy, valve means at the lower end of said tubular vessel openable to permit the molten alloy to flow in, valve means at the upper end of said tubular vessel openable to atmosphere, one way acting means permitting part of the hot water to enter the vessel, a discharge port at the lower end of said vessel opening into a delivery pipe leading to above water level, means for opening and closing both of said valves, a perforated extension on the lower end of said tubular vessel intended to rest on the bottom of the tank, means for introducing gaseous fluid under pressure into said vessel to create a fluid pressure therein which will drive the water downwardly in said vessel to force the molten alloy therein out through said discharge port and said delivery pipe, and means for securing said tubular vessel in the tank.

FRANCIS STEPHEN PILKINGTON.
